UNITED STATES PATENT OFFICE

2,432,952

APPARATUS FOR VACUUM DRYING PACKAGES OF YARN HAVING MEANS FOR ROTATING THE PACKAGES

Pieter H. van Scherpenzeel, West Asheville, N. C., assignor to American Enka Corporation, Enka, N. C., a corporation of Delaware

Original application February 11, 1946, Serial No. 646,877. Divided and this application June 6, 1947, Serial No. 752,861

6 Claims. (Cl. 34—92)

1

The present application is a division of my application Serial No. 646,877, filed February 11, 1946.

This invention relates to an apparatus for the drying of packages of rayon and similar textile yarns of threads and more particularly to an apparatus constituting improvements over those disclosed in U. S. Patent No. 2,266,375, issued December 16, 1941, reference to which is hereby made.

U. S. Patent No. 2,266,375 describes and claims a method of drying rayon packages under a controlled vacuum in a closed container to effect the drying of the rayon at lower temperatures than would otherwise be possible, the drying of the packages proceeding from the inside to the outside thereof. An apparatus for practicing the method is also described and claimed in the said patent. In this connection it is to be noted that the container is provided with a number of heating cylinders extending inwardly from one end wall thereof. The cylinders are each open at their fixed ends to permit the circulation of a heating medium therethrough, the cylinders being closed at their unsupported ends to confine the heating medium to the interiors thereof. Rayon packages may be assembled on the cylinders in any convenient manner, e. g., as shown in the patent, they may be arranged in side-by-side relationship on loading tubes which are adapted to slide snugly over their respective cylinders. Each of the tubes is of such diameter with respect to the rayon packages that it is sufficiently small to permit complete contraction of the rayon in the packages during drying.

Despite the fact that the patentees intend that all heat be directly applied to the packages through the medium of the cylinders and that they disclosed the presence of insulation material as a lining for the container, it has been determined that in the use of such an apparatus the drying does not proceed entirely as desired since some drying actually takes place prematurely in those segments of the outer portions of the packages which are adjacent or near the shell of the container. This premature drying in the outer portions of said packages is due to the radiation of heat from the shell of the container. The drying of rayon in those portions of the outsides of the packages before the respective interiors of the packages creates tension in the outer portion and causes shrinkage differences in the packages which in turn produces a barre effect in weaving and creates uneven dyeing characteristics in the threads.

2

It is an object of the present invention to provide means for drying packages of rayon which involve the rotation of the rayon packages during such drying operation so that all portions of the outside of the packages are exposed to the shell of the container for substantially the same time during the drying period.

It is a further object of the invention to effect the drying of packages of rayon under a high vacuum and by a heating medium substantially confined to the interiors of the packages whereby the drying takes place from the inside to outside thereof, and to avoid objectionable premature drying which might normally occur in segments of the outer portions of packages positioned near the container shell by effecting periodic partial rotation of said packages during the drying period.

Another object of the invention is to provide a drying apparatus having rotatably mounted loading tubes on those heating cylinders positioned adjacent or near the shell of the container so that the loading tubes supporting the packages exposed to radiation of heat from the shell may be rotated at intervals during drying.

This invention also contemplates the provision of a drying apparatus having a plurality of parallel rotatably mounted loading tubes arranged within a container adjacent or near the shell thereof in which the tubes are geared together for simultaneous rotation, and in which exterior means are provided for effecting partial rotation of the tubes.

Other objects and advantages will be apparent from the following detailed description when considered in connection with the accompanying drawings, wherein:

Figure 1 is a side elevational view of one form of apparatus made in accordance with this invention, the container being partially broken away to show the mechanism for rotating the loading tubes; and

Figure 2 is a transverse sectional view through the apparatus illustrated in Figure 1, showing the arrangement of the heating cylinders and the loading tubes with gears for rotating the packages positioned adjacent the cylindrical shell of the container.

Referring to the drawings in detail there is shown a vacuum drier generally indicated at 10. This drier is constructed similarly to the one shown in the above-mentioned patent and contains all of the elements thereof. It is contemplated that a large number of heating cylinders 11 be utilized and arranged in the manner indi-

cated in Figure 2. Heating cylinders 11 are fixed to extend from plate 12. Packages of rayon 13 are positioned on loading tubes 14 which are slidably mounted on the cylinders 11. Those loading tubes 14 which form the outer row adjacent the cylindrical shell 15 of the vacuum drier 10 are each provided at their inner ends with a gear 16. Said loading tubes are annularly arranged with their respective gears 16 in mesh with adjacent ones of the series and therefore the partial rotation of one of the tubes of the outer row will result in the rotation of each of the said tubes.

Whereas in the drawings, only the extreme outer row of loading tubes 14 are shown provided with gears 16 to effect rotation of the tubes, it is contemplated that the next adjacent row or rows may also be provided with similar gears in case it is necessary to rotate the same during drying.

Gearing designated generally at 17 is provided for driving the gears 16. Gearing 17 includes a spur gear 18 which meshes with the lowermost gear 16 of the series. Gear 18 is keyed to counter shaft 19 which shaft is suitably supported in bearings fixed on plate 20 by means of standard 21. Plate 20 constitutes a cover for an opening 22 in the shell of the drier 10. A bevel gear 23 is mounted on the end of shaft 19 remote from gear 18. Bevel gear 23 meshes with a bevel gear 24 mounted on vertical shaft 25. Shaft 25 extends down through a stuffing box bearing assembly 26 and plate 20 so that driving of the gear train may be effected from outside of the vacuum drier. Any suitable means for rotating shaft 25 may be employed such as a ratchet lever, wheel or crank (not shown). Shaft 25 may be operated either manually or automatically. While container 10 may be lined with insulating material as shown in the said patent the lining is not essential when the loading tubes adjacent the container are constructed for rotation as described.

In practicing the present method in the drier as described, rayon packages are first assembled on all of the loading tubes 14 and the tubes with the packages thereon are deposited over the heating cylinders 11. It is to be understood that those loading tubes 14 to which the gears 16 are secured are deposited upon the heating cylinders of the outer annular row or rows of cylinders whereas the normal tubes are deposited upon the inner cylinders. At this stage the drier is hermetically sealed and evacuated to a high vacuum. A heating medium is circulated through the closed cylinders in the manner described in U. S. Patent No. 2,266,375 so that the packages on the tubes are dried progressively from the inside to the outside. At intervals the cylinders located adjacent or near the shell of the drier are partially rotated. The extent of such rotation and the time intervals between each rotating operation are dependent on the particular conditions employed. It has been determined that turning the tubes 90° to 180° every 8 to 16 hours eliminates most of the irregularities which would normally occur during drying and that rotating the said tubes and packages of rayon thereon 90° every 12 hours is especially suitable under the conditions employed in the referred to patent. It is of course understood that the packages should not be turned in either direction so that they are out of their original positions more than 180° at any one time.

It is to be understood that various modifications, such as using more than one gear train for

rotating the tubes, may be made in the apparatus without departing from the spirit and scope of the invention which is to be limited only to the extent of the appended claims.

5. What is claimed is:

1. An apparatus for drying rayon packages having thread-free centers which comprises a container, means for hermetically sealing the same, a plurality of imperforate heating cylinders fixedly arranged in the container, loading tubes adapted to support rayon packages thereon and to removably fit over the cylinders, means on the loading tubes near the shell of the container for rotating the loading tubes at will during the drying operation and means for evacuating the container.

2. An apparatus for drying rayon packages having thread-free centers which comprises a container, means for hermetically sealing the same, 20 a plurality of imperforate heating cylinders fixedly arranged in the container, loading tubes adapted to support rayon packages thereon and to removably fit over the cylinders, gears on the inner ends of the loading tubes near the shell 25 of the container for rotating the loading tubes at will during the drying operation, means for driving the gears from the outside of the container and means for evacuating the container.

3. A drying apparatus for rayon packages having thread-free centers comprising, an annular chamber provided with an open end, a removable door for closing said chamber, sealing means between the door and the chamber, annularly arranged rows of parallel imperforate heating elements extending inwardly parallel to the horizontal axis of the shell of the chamber, loading tubes for receiving packages of rayon thereon, one of said tubes fitting over each of the heating elements and closely engaging the same, said loading tubes that are mounted on the heating elements of the outer annular rows each being provided with a spur gear fixed to its end remote from the door, the spur gears on the tubes meshing to form a continuous gear chain, a gear fixed 45 in position within the chamber and meshing with one of the spur gears of the chain, means for rotating the said gear which in turn effects the rotation of each of the tubes of the outer row with the packages thereon, and means for evacuating the chamber.

4. A drying apparatus for rayon packages having thread-free centers comprising, an annular chamber, parallel imperforate heating elements extending inwardly from a plate constituting the end wall of the chamber, loading tubes for holding packages of rayon, said tubes being detachably positioned upon the heating elements and being rotatably mounted thereon, the tubes each being provided with a spur gear fixed to its end adjacent the plate, said gears on the tubes meshing to form a continuous gear chain, means for rotating the gears of the train to effect the rotation of each of the tubes with the packages thereon and means for evacuating the chamber.

5. A drying apparatus for rayon packages having thread-free centers comprising, an annular chamber, means for evacuating the chamber, rows of parallel imperforate heating elements extending inwardly parallel to the horizontal axis of the shell of the chamber, loading tubes for receiving packages of rayon thereon, said tubes being snugly mounted upon the heating elements, a series of the loading tubes each being provided with a spur gear fixed to its inner end and meshing to form a continuous gear chain, a gear fixed

in position within the chamber for meshing with one of the spur gears of the chain when the carrier tubes are in operative position, a shaft for said fixed gear, a vertical shaft extending through the shell of the chamber, bevel gears connecting the said shafts and a stuffing box surrounding the vertical shaft, whereby the rotation of the vertical shaft will effect the rotation of the gears of the chain with their respective carrier tubes and the packages positioned thereon.

6. A drying apparatus for rayon packages having thread-free centers comprising, an annular chamber provided with an open end, a sealed door for closing said chamber, annularly arranged rows of parallel imperforate heating tubes extending inwardly parallel to the horizontal axis of the shell of the chamber, two sets of loading tubes for receiving packages of rayon thereon, the loading tubes of each set each being removably positioned over and snugly engaging one of the heating tubes, the loading tubes that comprise the set mounted on the respective heating elements of the outer annular rows each being provided with a spur gear fixed to its inner end, the spur gears on said

tubes meshing to form a continuous gear chain, a gear fixed in position within the chamber and meshing with one of the spur gears of the chain, means for rotating the said gear which in turn effects the rotation of each of said loading tubes of the outer rows together with the packages thereon and means for evacuating the chamber.
